United States Patent Office

Des. 190,636

Patented June 20, 1961

190,636

TRAILER HITCH BALL COVER

Raphael Schlosser, 9046 E. Burnside St., Portland, Oreg.

Filed Sept. 16, 1958, Ser. No. 52,658

Term of patent 14 years

(Cl. D14—6)

Fig. 1.

Fig. 2.

Fig. 3.

FIG. 2 is a side elevation thereof; and

FIG. 3 is a bottom plan view thereof.

I claim:

The ornamental design for a trailer hitch ball cover, as shown.
